UNITED STATES PATENT OFFICE.

JOSEPH BURGER, OF RICHMOND HILL, NEW YORK.

DOWELING MACHINE.

Application filed July 10, 1923. Serial No. 650,599.

The objects of this invention are to provide a simple practical machine for driving a dowel reinforcement or the like into a wood heel or other article, which will be practically automatic in its operation and will be readily adaptable to meet different conditions and requirements.

In the accompanying drawings there is illustrated an embodiment of the invention wherein the foregoing and other objects are attained but as this illustration is primarily for purposes of disclosure, it will be understood that the structure may be modified without departure from the true spirit and scope of the invention as hereinafter defined and claimed.

Figure 1 is a side elevation and part sectional view of the machine.

Figure 2 is a broken front elevation of the same.

Figure 3 is a horizontal sectional view on substantially the plane of line 3—3 of Figure 1, showing particularly the adjustable work rest or support.

Figure 4 is a vertical sectional view on substantially the plane of line 4—4 of Figure 1 of the adjustable eccentric for imparting a variable stroke to the driving head.

Figure 5 is an enlarged broken vertical sectional view as on substantially the plane of line 5—5 of Figure 2.

Figure 6 is a fragmentary horizontal sectional view of the hold-down clutch mechanism as on substantially the plane of line 6—6 of Figure 5.

The machine in the present disclosure is designed for use in the manufacture of wood heels and the various parts of the machine are therefore constructed with this end in view.

Thus the work holder or support is in the form of a table 7 of a size to support a wood heel 8 and pivoted at 9 so that it may be tilted to accommodate the style of the heel.

The tilting adjustment is effected by means of a screw 10 which serves to shift a post 11 slidably mounted in a guide-way 12 below the work table, said post having a supporting engagement with the under side of the table, as indicated in Figures 1 and 5.

The work is positioned upon the table by means of a gage 13 shown in Figure 5 as slidably guided in a slot 14 in the table and adjustably positioned therein by the screw 15.

The adjustable work support may also be

bodily raised and lowered in the illustration by means of a screw 16, operating in a screw seat 17 in a part of the frame of the machine and engaging the vertically adjustable bed 18 of the work support which can slide in vertical guide-ways 19. A lock nut 20 on the adjusting screw 16 serves to secure the bed carrying the work support in its vertically adjusted relation.

The dowel driving mechanism includes in the present disclosure a vertically reciprocating head 21 carrying a one-way driving clutch having a guide passage 22 for the dowel rod 23 with radially disposed dogs 24 pivoted at the lower end of the same at 25. These dogs have outwardly extended arms acted on by springs 26 which rock the dogs in a direction to thrust the points at the lower ends of the same inwardly into engagement with the dowel rod.

The driving head is shown as carried by slide rods 27 operating in vertical guides 28 and connected together at their lower ends by a cross bar 29 to which there is pivoted at 30 an eccentric rod 31. The lower end of the rod 31 is shown as provided with an eccentric strap 32 engaged about an eccentric 33 on the drive shaft 34.

A special feature of the eccentric is that it is mounted adjustably upon its shaft for the purpose of varying the stroke imparted to the drive head. This adjustable mounting is effected in the illustration by forming the eccentric with a slot 35 extending inward from near one edge thereof so that it may be adjusted radially of the shaft and by securing it to the face of a disc 36 fast on the shaft by bolts 37 extending through slots 38 in the disc, parallel to the slot in the eccentric. As an aid to adjustment the eccentric is shown as carrying a set screw 39 at the side of the same, extending radially inward into engagement with the adjacent edge of the disc 36.

With the construction described it is possible to vary the throw of the eccentric and hence the stroke of the drive clutch by simply loosening the securing screws 37, adjusting the set screw 39 and then tightening the screws 37 after the eccentric has been shifted to its new radial position upon the shaft.

To hold the dowel rod in the position to which it is advanced in the active stroke of the drive clutch and to prevent it from following the drive clutch during its return

stroke, there is provided in the illustration a one-way acting hold-down clutch consisting of a pair of spur wheels 40 adapted to grip the dowel rod between them and provided with ratchets 41 engaged by spring pawls 42 and faced to permit rotation of the spur wheels with the downward feed of the dowel rod and to prevent rotation of said wheels in the reverse direction. These spur 10 wheels, by gripping the dowel rod, serve to guide the same and also operate as an effective one-way clutch to hold the dowel as fast as it is advanced and prevent it from following the drive clutch upon the retractive movement of the latter.

To provide for a certain amount of adjustment of the rod gripping rolls, the latter are shown as carried by blocks 43 slidably engaged in a guide-way 44 and one 20 acted on by a set screw 45 and the other by a stud 46 projecting from a handle 47 which has at its outer end a lug 48 bearing on a cam track 49. The stud 46 serves as a swivel for the handle and it will be evident that 25 when the handle is swung forwardly and downwardly to free the lug 48 from the cam track 49, the cooperating pressure of the spur wheels on the dowel rod will be released or reduced so that the rod can be shifted or 30 removed from position therebetween.

The rod is cut off at the proper dowel length in the machine disclosed by an automatic cutter comprising a knife 50 carried by a slide 51 operating in a horizontal way 35 52 and cooperating with relatively fixed cutter edge 53. The cutter slide is shown as provided at its outer end with an inclined cam slot 54 engaged by pin 55 on the upper end of the slide rod 56 which carries at its 40 lower end a shoe 57 positioned to be engaged by an eccentrically disposed roll 58 on the drive shaft 34.

The cutter mechanism is preferably constructed to leave the dowel rod with a somewhat pointed end, as indicated, so that the same will readily enter the hole provided for it in the heel or other article. In the illustration this pointing effect is obtained 45 by constructing the cutter blades so that in completing the cut, the end of the rod will be squeezed or crushed into the semblance of a point.

Where the dowels are of wood or similar 55 material it is usually desirable to provide an adhesive for securing them in place. In the illustration this is effected by the provision of a cup 59 at the upper end of the passage 22 in the driving head which receives glue or other adhesive from a tube 60 extending from a reservoir 61. The lower 60 end of this tube is shown as having a guard 62 partially surrounding the dowel rod and the flow of adhesive is controlled by a valve 63 interposed at a suitable point in the line 65 of tubing.

The adhesive reservoir is shown as held in an adjustable clamp 64 carried by a bracket 65 attached to the drive head. The reservoir therefore partakes of the up and down movement of the drive head, which 70 movement has a tendency to facilitate the flow of adhesive. To make the adhesive flow more positive, there is indicated a piston 66 within the reservoir carried by a rod 67 fixed to the ceiling or other stationary support. This piston is shown as having a flap 75 valve 68 which opens on the down stroke of the reservoir and closes upon the up stroke of the reservoir so as to apply pressure and force out a certain quantity of adhesive upon each up stroke of the head.

The operation of the machine illustrated is controlled by a one-revolution clutch indicated generally at 69 which is tripped into action by a rod 70 connected with a conveniently located pedal (not shown).

In using the machine the adjustable eccentric is set to produce a driving stroke sufficient for the length of dowel which it is desired to drive and the work rest and gage are adjusted to support the work in proper position to take such a dowel. It is then only necessary to place the heel or other article upon the work rest and trip the control clutch, whereupon, with one revolution of the shaft, the drive clutch will force the dowel rod down through the hold-down clutch into the hole in the heel, the cut-off will sever the rod just above the heel 100 and the hold-down clutch will hold the remainder of the rod in this advanced position during the return of the drive clutch to its uppermost position. In this return movement a measured quantity of the adhesive will be forced out into the cup surrounding the upper portion of the rod so that the subsequently driven dowels will receive their proper measure of adhesive.

To insure proper stoppage of the parts at the end of a cycle of operations initiated by the press clutch an automatic brake, such as indicated at 71, may be provided on the drive shaft.

What I claim is:—

1. In a machine of the character disclosed, a reciprocating head, a one-way rod engaging clutch carried by said head, an adhesive reservoir carried by said head and having a supply passage extending to the clutch and a work rest for positioning the work to receive a dowel rod advanced by the clutch.

2. A combination as in claim 1 with means supported from a fixed point and cooperating with the reciprocating reservoir to apply pressure to the adhesive therein.

3. A combination as in claim 1 in which the reservoir is adjustably mounted on the reciprocating head and a piston within the reservoir is supported from a relatively

fixed point so as to apply pressure to the adhesive in the reciprocating movements of the reservoir.

4. In a machine of the character disclosed, a driving clutch having a dowel rod passage therethrough with an adhesive cup at the upper end of the same and a clutch dog at the lower end of the same and a support in the line of travel of the dowel rod advanced by said clutch.

5. In a machine of the character disclosed, means for advancing a dowel rod, a guide for the rod including rolls between which the rod passes and pawl and ratchet mechanism for preventing retrograde movement of said rolls, one of the rolls being carried by a block having an adjustable mounting and a cam lever releasably holding said block in place.

6. In a machine of the character disclosed, a reciprocating head, a one-way operative rod driving clutch carried by said head, a reversely operative one-way rod holding clutch in line with the rod driving clutch, a support for positioning the work in line with the clutches and variably adjustable to locate the work at different angles and different distances from the clutches and means for varying the effective stroke of the drive clutch in accordance with the adjustments of the work support and means for automatically supplying adhesive to the rod held in the driving clutch irrespective of the various adjustments of the several parts described.

7. In a machine of the character disclosed, a driving clutch having a dowel rod pas-

sage, means for automatically supplying adhesive to a dowel engaged in said passage and a work support in the line of the dowel rod advanced by the clutch.

8. In a machine of the character disclosed, a reciprocating head, a one-way rod driving clutch carried by said head, an adhesive reservoir having a supply passage extending to said clutch, means for automatically forcing the adhesive under pressure through said supply passage to the clutch and a rest for positioning the work to receive the dowel rod advanced by the clutch.

9. In a machine of the character disclosed, a one-way operative reciprocating dowel driving clutch, a bed adjustable longitudinally of the driving stroke of the clutch, a heel supporting table pivotally mounted on said bed, a member for tilting said table to vary the angle of the heel with respect to the dowel and a gage adjustable on said tilting table for positioning the heel laterally in respect to the dowel.

10. In a machine of the character disclosed, a reciprocating rod driving clutch, a support for positioning the work in line with the rod advanced by the clutch, means for automatically supplying adhesive to the rod held by the clutch, spur wheels positioned to bite into the rod advanced by the clutch and pawl and ratchet mechanism for holding said spur wheels against retrograde movement to thereby positively hold the rod in the advanced position.

In witness whereof, I have hereunto set my hand this 26th day of June, 1923.

JOSEPH BURGER.
